O. BECKER
HOLDER FOR FLAT FILMS WITH CLAMPING DEVICES
FOR THE EDGES OF THE FILMS
Filed April 29, 1927

UNITED STATES PATENT OFFICE.

OSCAR BECKER, OF BERLIN-TREPTOW, GERMANY, ASSIGNOR TO I. S. FARBENINDUSTRIE AKTIENGESELLSCHAFT, OF FRANKFORT-ON-THE-MAIN, GERMANY.

HOLDER FOR FLAT FILMS WITH CLAMPING DEVICES FOR THE EDGES OF THE FILMS.

Application filed April 29, 1927, Serial No. 187,609, and in Germany May 5, 1926.

The present invention relates to a holder for films during development and other treatment of the films whilst in an upright (that is a vertical) position in which the film is gripped by a clamping device that is entirely reliable in its action.

The chief feature of the present invention is that in spite of the fact that the edges of the film are immovably gripped the film is easily inserted in the holder with or without a special insertion device owing to the fact that the clamping devices are formed with funnel-shaped entrance slots for the film. This enables the flat film, which is highly sensitive and coated on both sides by emulsion, to be inserted accurately without danger of damage. The various clamping devices have rims formed by the upwardly bent edges of a plate member and in connection with these rims and besides them an arm movable in a plane parallel to them, which arm, if it is downwardly displaced, bends the edge of the film acutely about one edge and thus grips it firmly. One form of construction of the invention is shown in the annexed drawings in which

Fig. 1 is a front view of a film holder.

Fig. 2 is a side view, and

Fig. 3 is a rear view of a clamping device on a larger scale.

Fig. 4 is a cross-section of the closed clamping device, that is with the movable arm in its lowered position, and

Fig. 5 is a cross-section of the clamping device open, that is with the movable arm raised.

As shown in Fig. 1, 1 is a rectangular frame which is preferably of bent wire, and of which the upper cross-member enables the frame to be handled, for example, for immersing it or hanging it in a bath. To the side members of this frame are secured clamping devices 2 for the edges of the film to be gripped.

Such a clamping device consists (see Figs. 2-5) of a plate member 3 bent out of a strip of metal of U-section, so that the shank portion 4 carries the edge members 5, between which is an entrance slot 6 for the

film. The front edges of these bent portions 5 are cut obliquely so that the insertion slot 6 broadens out in an upward direction, and consequently it is easily possible to insert the film in the clamping device from above. Inserted in this way, the film lies in the neighbourhood of its side edges upon the narrow edge 7 of one of the bent portions 5 of the clamping device 2. In proximity to the bent portion 5 the spring arm 8 is secured to the plate member 3 in such manner that its under surface is not normally in the position shown in Fig. 3 behind or in front of the member 5, but, lying inside the shank of the plate member of U-shaped cross-section, leaves the funnel-shaped insertion slot open. In an opening in the member 4, an eccentric 9 is movably mounted on the pin 10, and is provided with a handle 11. This eccentric rests on the upper surface of the arm 8. If the eccentric is rotated owing to movement of the handle 11 so that the eccentric bears against the shank 4 of the member 3, the eccentric bears upon the arm 8, which is pressed to pass the edge 7 (see Fig. 4) and bends the edge of the film located at the narrow edge of the bent portion 5 about this narrow edge, and immovable clamping of the edge of the film in the clamping device is thus attained.

Having now particularly described and ascertained the nature of my said invention and in what manner the same is to be performed, I declare that what I claim is:

1. A holder for flat films provided with a clamping device for the edges of the films characterized by the fact that the clamping devices are provided with funnel-shaped slots for the edges of the films.

2. A holder for flat-films according to claim 1, characterized by the fact that the holder comprises an edge upon which the film lies and over which it is bent about its edge by means of an arm movable laterally of the strip on the downward movement of a lever provided with an eccentric.

3. A holder for flat films according to claim 1 characterized by the fact that the clamping device consists of a member formed by bending a metal plate, of which the arms

are once so bent at their front portions that a slot is formed between the latter for the insertion of the film, which bears upon the narrow edge of the bent central portion.

5 4. A holder for flat films according to claim 1 characterized by the fact that in the plate member formed by bending, a leaf

spring is arranged as a swinging arm for pressing down the inserted film, which spring can be pressed down by means of an eccentric movably positioned in one of the arms of the frame. 10

In testimony whereof I affix my signature.

OSCAR BECKER.
